UNITED STATES PATENT OFFICE.

WALKER B. GILBERT, OF LYNCHBURG, VIRGINIA.

HOOP-STRETCHING DEVICE.

1,421,935.

Specification of Letters Patent.

Patented July 4, 1922.

Application filed August 21, 1920. Serial No. 405,109.

To all whom it may concern:

Be it known that I, WALKER B. GILBERT, a citizen of the United States, residing at Lynchburg, in the county of Campbell and State of Virginia, have invented certain new and useful Improvements in Hoop-Stretching Devices, of which the following is a specification.

This invention relates to improvements in hoop stretching devices, and more particularly to a type thereof adapted for stretching the head or end hoops of tobacco hogsheads after the head of the latter has been properly positioned in the end of the same.

The primary object of the invention is to provide for a device of the character mentioned, and one involving extreme simplicity and durability and construction and arrangement as well as ease in application and operation.

A further object of the invention is to provide for a device of the type set forth, and one of comparatively inexpensive construction, and in which, the parts thereof are interchangeable in form to admit of the quick replacement of parts in case of breakage and wear.

With the foregoing and other objects in view, the invention resides in the certain novel construction and arrangement of parts as will be hereinafter more fully described, set forth in the appended claims, and illustrated in the accompanying drawing, in which:—

Figure 1 is a top plan view of the device as applied to the end of a barrel or hogshead, and showing its mode of operation.

Figure 2 is a side elevation of the same as in Figure 1, and

Figure 3 is a transverse section on the line 3—3 of Figure 1.

Referring to the drawing, in which similar characters of reference designate corresponding parts in the several views thereof, the numeral 1 indicates a fragmentary section of a barrel or hogshead, or other similar container made up of staves and otherwise involving the use of encircling securing bands or hoops, and the numeral 2 indicates one of the said securing bands or hoops and preferably that one of the latter encircling the staves immediately adjacent the ends of the barrel or hogshead.

The stretching device comprises a clamp

arc of a circle to adapt the same to the curvature of a barrel or hogshead, and a pair of spaced, substantially inverted U-shaped clamping elements or hooks 11, which have one leg suitably secured to the bar 10, or, if desired, formed integrally with the latter, and which are adapted to be fitted over the edge of the wall of the barrel or hogshead, in a manner to retain one end portion of the hoop 2 between the outer face of the barrel or hogshead and the inner face of the bar 10, the adjacent free end of the hoop 2, as at 3, projecting for a short distance to one side of the bar 10, as shown. A clamp screw 12 is threaded into an opening in one of the clamping hooks and the bar, and, when operative, has its inner end contacting the opposed face of the hoop so as to firmly hold the latter and the clamp frame, as a whole, against slippage during the stretching operation.

Immediately adjacent one of the clamping hooks 11 is secured, to the outer face of the bar 10, one leg 13 of a substantially L-shaped bracket which has the other of its legs 14 projecting outwardly from the bar 10 at right angles to the same and to the leg 13. It is to be here noted that that right handed clamp hook may be separately secured to the bar 10, as shown, or the same may readily be formed integrally with the leg 13 of the bracket member as may be desired.

Formed with and at one side of the leg 14 of the bracket are a pair of vertically spaced ears 15 which are provided with aligned openings to receive the upper and lower trunnions 16 of a bearing block 17, the latter being disposed in alignment with and centrally of an opening 18 formed in the leg 14 in a plane medially between the ears 15.

Threaded through an opening formed in the bearing block 17 and projecting through the opening 18 in the leg 14 of the bracket, for a distance to either side thereof is a main screw or stretcher rod 19, which terminates at one of its ends, preferably its right handed end as shown, in a substantially U-shaped yoke or fork 20, into which is received the adjacent end of a clamp plate 21, whereby to provide a swivel or hinged joint connection between the latter and the screw stretcher rod. The major length of the screw stretcher rod 19 is threaded, and carries a hand wheel 22 which is arranged to abut the bearing

block 17 when operated to feed the screw stretcher rod backward and forward therethrough.

The clamp plate 21 is formed with or has secured thereon an enclosed clamping yoke or member 23 which is adapted to receive the free end 4 of the securing band or hoop 2, and a clamp or set screw 24 is threaded through the outer wall of the yoke or member 23 in a manner to securely hold the hoop end within the yoke, when its inner end is forced into contact with the same for such purpose.

With the parts assembled as described, and the device applied to the end of a barrel or hogshead as shown in the drawing, it will be readily apparent that the hoop end 3, contacting the outer wall of the barrel or hogshead, will be securely held against all possible slippage, and that, when the intermediate portion of the hoop has been properly positioned in its encircling relation around the barrel or hogshead, and its end 4 engaged in the yoke 23, upon the manipulation of the hand wheel 22, any amount of stretching may be done to the hoop within the range of the threaded end of the screw stretching rod 19, the hoop ends 3 and 4 being held in aligning and overlapping relation, so that the securing or fastening devices may be applied to secure the hoop, in its entirety, to the barrel or hogshead, while under tension, without further manipulation of the device, or disturbing it in any way, or moving from its original position.

From the foregoing, it will be obvious that the invention provides for an extremely simple device in construction, application and operation, as well as one, in the use of which, maximum efficiency and results are to be obtained.

It is well understood that various changes in size and detail of construction and arrangement of parts may be resorted to without departing from the spirit and scope of the invention.

Having thus fully described my invention, what I claim is:

1. In a device of the class described, means conformable to the curvature of the side wall of a barrel for clamping one end of a hoop in position thereon, means for securing said first mentioned means in position, and means associated with said first-mentioned means for engaging the other end of the hoop and stretching the latter prior to the securing of the same to the wall of the barrel.

2. In a device of the class described, means engageable with the peripheral wall of a barrel for clamping one end of a hoop in position thereon, means for retaining said first mentioned means in operative position, means associated with said first mentioned means for engaging the other end of the hoop in overlapping relation with respect to

the clamped end thereof, and means for manipulating said last-mentioned means for stretching the hoop prior to the securing of the same to the wall of the barrel.

3. In a device of the class described, means for clamping one end of a hoop in position to encircle the side wall of a barrel, means engageable with the end of the barrel for retaining said first mentioned means in operative position, means associated with said clamping means for engaging the other end of the hoop, and means for manipulating said last-mentioned means for stretching the hoop, said means being adapted to hold the adjacent hoop ends in aligning and overlapping relation, after the stretching operation, subject to the application of fastenings to secure the hoop permanently in position on the wall of the barrel.

4. In a device of the class described, a curved clamping member adapted to be on the side wall of a barrel and to engage one end of an encircling hoop, means adapted to be engaged over the end edge of the barrel for retaining said clamping member in position, a clamping element adapted to engage the other end of the hoop and hold the same in aligning relation with respect to the first-mentioned end thereof, and means for manipulating said clamping element for stretching the hoop and to draw the adjacent ends thereof into overlapping relation and to hold the same in position subject to the application of fastenings to secure the hoop permanently in position on the wall of the barrel.

5. In a device of the class described, a bar curved to conform to the contour of a barrel, clamping members carried by said bar and adapted to be engaged over the end edge of the barrel to hold the bar in aligning contact with a portion of one end of a hoop encircling the barrel, a clamping element carried by said bar and adapted to engage the other end of the hoop and hold the same in aligning relation with the clamped end of the hoop, and means for manipulating said clamping element for stretching the hoop and to draw the adjacent ends thereof into overlapping relation and to hold the same in position subject to the application of fastenings to secure the hoop permanently in position on the wall of the barrel.

6. In a device of the class described, a bar curved to conform to the contour of a barrel, clamping members carried by said bar and adapted to be engaged over the end edge of the barrel to hold the bar in aligning contact with a portion of one end of a hoop encircling the barrel, a clamping element carried by said bar and adapted to engage the other end of the hoop and hold the same in aligning relation with the clamped end of the hoop, and screw operated means for manipulating said clamping element for stretching the hoop and to draw the adjacent ends

thereof into overlapping relation and to hold the same in position subject to the application of fastenings to secure the hoop permanently in position on the wall of the barrel.

- 5 7. In a device of the class described, a
clamping frame curved to conform to the
contour of a barrel and adapted to be en-
gaged over the end edge of the latter and to
retain one end of a hoop in position against
10 the outer wall of the barrel, a stretching rod
carried by said frame, a clamping element
carried by said stretching rod and adapted
to engage the free end of the hoop, and
means for manipulating said stretching rod
15 for stretching the hoop and to draw the ad-
jacent ends thereof into overlapping relation
and to hold the same in position subject to
the application of fastenings to secure the
hoop permanently in position on the wall of
20 the barrel.

8. In a device of the class described, a

clamping frame curved to conform to the
contour of a barrel and adapted to be en-
gaged over the end edge of the latter and to
retain one end of a hoop in position against 25
the outer wall of the barrel, a bracket car-
ried by said clamping frame, a bearing block
trunnioned in said bracket, a stretching rod
threaded in said bearing block, a clamping
element adapted to engage the free end of 30
the hoop and having a swivel connection
with one end of said stretching rod, and a
hand wheel for manipulating said stretch-
ing rod for stretching the hoop and to draw
the adjacent ends thereof into overlapping 35
relation and to hold the same in position
subject to the application of fastenings to se-
cure the hoop permanently in position on the
wall of the barrel.

In testimony whereof I affix my signature. 40

WALKER B. GILBERT.
